Oscar Geier

UNITED STATES PATENT OFFICE.

CHARLES BERBERICH, OF WATERBURY, CONNECTICUT.

CIGAR-TIP CUTTER.

1,336,724.

Specification of Letters Patent. Patented Apr. 13, 1920.

Application filed January 14, 1918, Serial No. 211,783. Renewed December 12, 1919. Serial No. 344,469.

To all whom it may concern:

Be it known that I, CHARLES BERBERICH, a citizen of the United States, resident of Waterbury, county of New Haven, and 5 State of Connecticut, have invented certain new and useful Improvements in Cigar-Tip Cutters, of which the following is a specification.

This invention relates to improvements 10 in pocket cigar-tip cutters, and has as its special object the provision of means whereby the end of an inserted object as a cigar may be clipped in an easy and expeditious manner.

15 This object is attained by the novel construction and combination of parts hereafter described and shown in the accompanying drawing, forming a material part of this disclosure, and in which—

20 Figure 1 is a side elevational view of a tip cutter made in accordance with the invention.

Fig. 2 is a partial vertical sectional view taken on line 2—2 of Fig. 1.

25 Fig. 3 is a similar view of the same parts shown in an extended position, and

Fig. 4 is a perspective view of the cutting device attached to the lower part of the casing.

30 In the drawing, the numeral 10 represents the casing or body of the cutter, which may for the purpose set forth be of any type whatever.

The casing has a band 11 secured at its 35 base by means of screw-threads, the band also engaging a cylindrical sleeve 12, the same extending at a considerable distance below the lower end of the casing and in register therewith, the sleeve 12 being partially enveloped in a telescope tubular jacket 14, the element having an inturned flanged bottom 15, the interior edges 16 of which are turned upwardly into an annular opening 17 at the base of the sleeve. The 40 flanges 15 and 16 provide an annular channel in which the outturned flange of the sleeve is adapted to be received when in its lowered position.

Intervening between the sleeve 12 and tubular element 14 is a band 20, secured to 50 the jacket 14, by rivets 21 and containing a side opening 22, registering with a similar opening 23, formed through the jacket walls 14 and also registerable with an opening 24, formed through the sleeve walls 12, so that 55 when the jacket is in a raised position, the end of a cigar or like article may be entered and upon the telescopic jacket 14 being moved upwardly toward the band 11, causes the same to be severed, the cut piece 60 dropping into jacket 14 and outwardly through the opening in its base.

The construction and manner of operation of the device is believed to be evident from the foregoing description, taken in 65 connection with the drawing.

Having thus described my invention, what I claim as new, and desire to secure by Letters Patent, is—

In a device as described, in combination, 70 a cylindrical sleeve, a band mounted at one end of said sleeve, a cylindrical jacket, a second band secured to the inner face of said jacket intermediate the ends thereof, and having a cutting edge, said cylindrical 75 sleeve telescoping within said second band and formed at its lower end with an outstanding annular flange engaging the interior wall of said jacket, an inturned flanged bottom formed with said jacket for 80 constituting with the inner wall of the jacket a channel in which the flange of said sleeve is adapted to be received, said jacket, second band and sleeve being provided with registering openings adapted to receive a 85 cigar tip, the edge of the opening in said sleeve being sharpened so as to provide a cutting edge adapted to coöperate with the cutting edge of said second band for cutting the tip off a cigar introduced into said openings upon the movement of said jacket toward the first named band, substantially 90 as described.

In testimony whereof I have affixed my signature.

CHARLES BERBERICH.
